UNITED STATES PATENT OFFICE

127,134

DESIGN FOR A DRESS

Herman Horowitz, Brooklyn, N. Y.

Application February 24, 1941, Serial No. 99,176

Term of patent 3½ years

To all whom it may concern:

Be it known that I, Herman Horowitz, a citizen of the United States, residing in the Borough of Brooklyn, county of Kings, city and State of New York, have invented a new, original, and ornamental Design for a Dress, of which the following is a specification, reference being had to the accompanying drawings, forming part thereof.

On the drawings,

Fig. 1 is a front elevational view of a dress embodying my design; and

Fig. 2 is a rear elevational view of the dress.

I claim:

The ornamental design for a dress, as shown.

HERMAN HOROWITZ.
